(57) **CLAIM**

The ornamental design for an aircraft weighing device, as shown and described.

DESCRIPTION

FIG. 1 is a top perspective view of an aircraft weighing device showing our new design;

FIG. 2 is a top view thereof;

FIG. 3 is a bottom view thereof;

FIG. 4 is an end view thereof;

FIG. 5 is an alternative end view thereof;

FIG. 6 is a side view thereof; and,

FIG. 7 is an alternative side view thereof.

The article is shown with a symbolic break in its length and width. The appearance of any portion of the article between the break lines forms no part of the claimed design.
